UNITED STATES PATENT OFFICE.

CHARLES L. TRUSLER, OF INDIANAPOLIS, INDIANA, ASSIGNOR TO THE
MCCOY, HOWE COMPANY, OF SAME PLACE.

DESIGN FOR A SUPPOSITORY.

SPECIFICATION forming part of Design No. 30,699, dated May 2, 1899.

Application filed February 16, 1899. Serial No. 705,733. Term of patent 14 years.

To all whom it may concern:

Be it known that I, CHARLES L. TRUSLER, a citizen of the United States, residing at Indianapolis, in the county of Marion and State 5 of Indiana, have invented and produced a certain new Design for a Suppository, of which the following is a specification.

Figure 1 is a top or plan view of my new design; Fig. 2, an edge view of same; Fig. 3, 10 a longitudinal section on the line 3 3 of Fig. 1; and Fig. 4, an end view looking in the direction of the arrow, Fig. 2.

My design consists of a sphenoidal or wedge-shaped body with four tapering sides. The 15 body is wider in one direction than it is in the other, and the two broadest sides thus produced are convexed or made to rise into a round form on the outside. The other two sides are straight. The four corners of the

small end of the suppository are rounded, and 20 the corners where the straight sides pass into the base of the suppository are also rounded.

A represents the two convexed tapering sides; B, the straight tapering sides; C, the base, and D the small end of the suppository. 25

Having thus fully described my invention, what I claim as new, and wish to secure by Letters Patent, is—

The design for a suppository substantially as herein shown and described. 30

In witness whereof I have hereunto set my hand and seal, at Indianapolis, Indiana, this 11th day of February, A. D. 1899.

CHARLES L. TRUSLER. [L. S.]

Witnesses:

JOHN C. MYERS,
HARRY C. PITMAN.
